UNITED STATES PATENT OFFICE.

JOSIAH H. EDWARDS, OF LOS ANGELES, CALIFORNIA.

SASH-PULLEY CASING.

No. 872,915.

Specification of Letters Patent.

Patented Dec. 3, 1907.

Application filed March 16, 1907. Serial No. 362,738.

To all whom it may concern:

Be it known that I, JOSIAH H. EDWARDS, a citizen of the United States of America, residing at Los Angeles, in the county of Los Angeles and State of California, have invented new and useful Improvements in Sash-Pulley Casings, of which the following is a specification.

This invention relates to sash pulley casings, and one of the principal objects of the same is to provide means whereby sash pulley casings may be supported in the window casing without the use of screws.

Another object of the invention is to provide a sash pulley casing which can be quickly attached in place, will not require the use of screws in attaching the same to the window casing, and which will be firmly held in place when attached.

These and other objects may be attained by means of the construction illustrated in the accompanying drawing, in which:

Figure 1 is a side elevation of a portion of a window casing and showing two of my sash pulley casings secured thereto in accordance with my invention. Fig. 2 is a transverse sectional view on line 2—2, Fig. 1.

Referring to the drawing for a more particular description of my invention, the numeral 1 designates the window casing, 2 is the parting strip, and 3 are the sash pulley casings, each comprising a bearing plate having inwardly extending arms 4 disposed within a mortise 5 in the window casing, and 30 journaled in the arm 4 are the trunnions 6 of the grooved pulley 7. The bearing plate for the pulleys are set in flush with the inner

surface of the window casing, as shown in Fig. 2, the flange 8 projecting at right angles to the arm 4. The opposite side of the bearing plate is provided with an integral face portion 9, an inwardly extending member 10, and a terminal angular flange 11. The members 10 and the flanges 11 are seated in the parting strip groove, and the parting strip 2 is driven in place against the lugs 11, thus holding the two pulleys firmly in place and permitting them to be removed after the parting strip 2 has been withdrawn.

From the foregoing it will be obvious that my sash pulley casings do not require the use of screws for holding them in place, that they can be quickly secured in the window casing, and can be quickly removed for repairs whenever required.

Having thus described the invention, what I claim is:

The herein described sash pulley casing comprising a plate having inwardly extending arms, a pulley journaled in said arms, a right angled flange extending from the inner edge of the plate into the parting strip groove of a window frame, such flange provided with an extension lying flush with the bottom of said groove, and a parting strip seated in the groove for binding the flange in place.

In testimony whereof, I affix my signature in presence of two witnesses.

JOSIAH H. EDWARDS.
